Primary Examiner — Michael A Maharajh(74) *Attorney, Agent, or Firm* — Dawn-Marie Bey; Bey & Crotopia PLLC(57) **CLAIM**

The ornamental design for a massage gun acupressure tip, as shown and described.

DESCRIPTION

FIG. 1 is a right side, exploded view of an massage gun acupressure tip, showing our new design;

FIG. 2 is a right side view shown in a condition of use;

FIG. 3 is a right side, back perspective view shown in a condition of use thereof;

FIG. 4 is a back view of the massage gun acupressure tip in FIG. 1; and,

FIG. 5 is a front view thereof.

Remaining views have no design elements or are duplicative, and thus are omitted.

The fitting attachment shaft shown in broken lines in FIGS. 1, 2 and 3 are for the purpose of illustrating environmental structure, which form no part of the claimed design.

The broken lines shown in FIG. 4 are for the purpose of illustrating portions of the massage gun acupressure tip, which form no part of the claimed design.
